UNITED STATES PATENT OFFICE.

FRANK W. WILLIAMS, OF CHICAGO, ILLINOIS.

DOUBLE-HORN CONSTRUCTION FOR GRAPHOPHONES.

Application filed September 10, 1921. Serial No. 499,672.

To all whom it may concern:

Be it known that I, FRANK W. WILLIAMS, a citizen of the United States, and a resident of the city of Chicago, in the county of 5 Cook and State of Illinois, have invented certain new and useful Improvements in a Double-Horn Construction for Graphophones; and I do hereby declare that the following is a full, clear, and exact description 10 of the same, reference being had to the accompanying drawings, and to the numerals of reference marked thereon, which form a part of this specification.

This invention relates to a new and improved phonograph horn construction in 15 which a double amplifying horn is used with the result that a greater volume of sound can be produced with the same or with even a less amount of cabinet space 20 underneath the disk supporting table. Heretofore a great deal of inconvenience and difficulty has been experienced by designers of phonograph cabinets on account 25 of the fact that the amplifying horn and the driving mechanism for the revolving disk supporting turn-table seriously interfered with each other because of the fact that the same space which would be most desirable 30 is not available for both.

Therefore, a primary object of this invention is to provide a phonograph horn in 35 which ample space for the driving mechanism remains after the phonograph horn has been inserted in the cabinet.

A further object of this invention is the provision of a double phonograph horn whereby the volume of sound issuing therefrom may conveniently and readily be regulated to any degree by merely adjusting the 40 position of one or both of the doors provided for the openings of the double horns.

A still further object of this invention is to provide a more compact and hence more neat appearing cabinet construction.

Other and further important objects of 45 the invention will be apparent from the disclosures in the specification and the accompanying drawings.

The invention (in a preferred form) is illustrated in the drawings and hereinafter 50 more fully described.

On the drawings:

Figure 1 is a top plan view of my improved form of phonograph cabinet showing 55 a record upon the revolving turntable.

Figure 2 is a section taken on the line 2-2 of Figure 1.

Figure 3 is a section taken on the line 3-3 of Figure 2, looking in the direction indicated by the arrows. 60

Figure 4 is a section, partly broken away, taken on the line 4-4 of Figure 2, looking in the direction indicated.

Figure 5 is a front view showing the doors 65 of the improved double horn.

As shown on the drawings:

The reference numeral 6 indicates a phonograph cabinet of ordinary construction having therein the usual revolving record holding table 7 cooperating with a reproducer 8 and a swiveled sound conducting tube or tone arm 9 which is held in position on the cabinet shelf by the usual plate 10. An opening 11 communicates between the sound conducting tube 9 and another 70 sound conducting chamber 12 of square cross section which extend transversely across the machine at the rear thereof directly underneath the base of the sound conducting tube 9. This second sound conducting chamber 12 is preferably made of wood or other suitable material and has at its further end two apertures 13 and 14 which in turn lead into connection with the double horns 15 and 16 respectively and 75 which are preferably of the shape shown in Figures 2 and 3. These horns are constructed of slantingly extending side members 17 and 18 and inclined bottom members 19 and 20 respectively, thereby forming 80 two similar tapered sound conducting tubes or amplifying horns both terminating at the front of the cabinet and closed by doors 21 and 22 respectively which slide upon each 85 other and are adapted to be opened to any desired degree by means of the knobs provided at 24 and 26.

It will be seen that by this construction 90 the entire middle portion of the cabinet directly underneath the revolving record holding table is left free to accommodate the driving mechanism of the graphophone, the proper positioning of which has heretofore caused serious inconvenience in designing the location of the sound conducting tube. Also by this method a much better 100 blending of the sounds can be produced as the sound waves are first divided in the sound conducting tube 12 and then separately amplified in passing through the double 105 110

horn construction 15 and 16 and upon issuing from same are again reunited before reaching the ear, thereby resulting in a much more pleasing effect.

5 As is also evident, the volume of sound produced can conveniently be divided in half by closing one of the doors, or otherwise regulated between the maximum and minimum limits by merely adjusting the 10 position of one or both of the sliding doors.

I am aware that the details of construction may be varied through a wide range without departing from the principles of this invention and I therefore do not pur- 15 pose limiting the patent granted otherwise than necessitated by the prior art.

I claim as my invention:

In a phonograph cabinet, an amplifier having a plurality of spaced outlets disposed in the side walls of the cabinet, and 20 sliding doors for said outlets each adapted to close one of said outlets, said doors when opened sliding one behind the other to occupy a common space between said outlets.

In testimony whereof I have hereunto 25 subscribed my name in the presence of two subscribing witnesses.

FRANK W. WILLIAMS.
